UNITED STATES PATENT OFFICE.

ETTA L. JENKINS, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 17,912, dated November 29, 1887.

Application filed October 15, 1887. Serial No. 252,507. Term of patent 3½ years.

To all whom it may concern:

Be it known that I, ETTA L. JENKINS, of the city, county, and State of New York, have invented and produced a new and original Design for a Pattern of a Girl's Dress; and I do hereby declare that the engraved prints accompanying this specification convey to any one accustomed to using paper patterns a clear understanding of how a garment made 10 up by the pattern will appear.

The design shows a round waist, fronts that display a closing down the center, a cluster of forward-turning tucks below the bust, and a fullness at each shoulder, a round waist-back

15 that is seamless at the center, a full skirt depending from the waist and exhibiting shirrings all round near the top, and two deep tucks below the shirrings, full sleeves that exhibit fine plaits below the elbow and gathers at the top, and a rolling collar. 20

What I claim as my invention, and desire to secure by Letters Patent, is—

The design for a girl's dress, as shown in the engraved prints accompanying this specification.
